UNITED STATES PATENT OFFICE.

OLIVER P. FRITCHLE, OF DENVER, COLORADO, ASSIGNOR TO THE FRITCHLE AUTOMOBILE & BATTERY CO., OF DENVER, COLORADO, A CORPORATION OF COLORADO.

CONTROLLING MECHANISM FOR ELECTRIC AUTOMOBILES.

1,127,427.

Specification of Letters Patent.

Patented Feb. 9, 1915.

Application filed September 2, 1913. Serial No. 787,824.

To all whom it may concern:

Be it known that I, OLIVER P. FRITCHLE, a citizen of the United States, residing at Denver, in the county of Denver and State 5 of Colorado, have invented certain new and useful Improvements in Controlling Mechanism for Electric Automobiles, of which the following is a specification.

This invention relates to a means for controlling electric automobiles, whereby the automobile will be made safe against accidental starting or reversing, or leaving its place when standing idle.

An object of my invention is to produce 15 a controlling mechanism that will prevent accidents due to unconscious movements of the levers, to be "fool-proof," and to effect the switching, locking, controlling, braking, reversing, and starting with the minimum 20 number of levers and wearing parts.

In the accompanying drawings, in which the invention is illustrated diagrammatically, Figure 1 is a view of the steering column and controller, showing a section of 25 the switch box and the relation of the various parts when the controller and switch are in the off-position; Fig. 2 shows a side view of the controller lever when raised to the upper reverse segment for reversing 30 the motor; Fig. 3 shown a plan view of the controller lever on the lower ahead segment of the switch box, on the line A—B, Fig. 1; Fig. 4 shows a plan view of the controller lever on the upper reverse 35 segment at full speed reverse position, on the line A—B, Fig. 1; Fig. 5 shows a sectional view of the switch box, on the line J—K Fig. 1, showing the switch thrown in, the controller being in the "off" position; 40 Fig. 6 shows a view of the switch box, on the line J—K of Fig. 1, with the switch "off," and the safety-pawl in the locking position; Fig. 7 shows the reversing switch and cam, on the line C—D, Fig. 1; Fig. 8 shows 45 a sectional view of the controller drum in the "off" position, on the line E—F, Fig. 1; and Fig. 9 shows the controller-spring-action cam for locking the controller at the various points on the line G—H, Fig. 1.

50 In Fig. 1, the lever 2 is connected at the joint 3 to the steering-shaft 35, which passes

through the controller-tube 9, and connects to the steering-crank 36, which in turn is connected to the steering rods connecting the wheels. The controller-tube 9 has adjacent its upper end a controller-sector casting and support 4, which carries the upper reversing-sector 5, and the lower ahead-sector 6. The lever 7, carrying an alarm push-button 8, is pivotally secured to the tube 9, 55 permitting a limited upward and downward movement, and also turning the tube 9 around the shaft 35 through about a quarter of a circle. The sectors 5 and 6 are in different planes, that is, out of alinement, as 60 shown in Figs. 1 and 2, and are spaced by a slot 20, as shown in Figs. 3 and 4, permitting the extension 51, containing slot 50, to pass to the upper and lower sectors 5 and 6, the slot 50 inclosing the sector as shown. 65 The stops, or extremities, 18 and 19 on sectors 5 and 6 limit the movement of the lever. 70

At the lower end of tube 9 is a miter gear 24, meshing with a similar gear 24', which latter is mounted upon shaft 34 carrying the 75 insulated drum 28 and segments 29, and reversing-switch cam 30. Upon the turning of the lever 7, shaft 34 is turned through the miter-gears; the drum 28 being locked in different positions by the cam 25, pawl 27, 80 and spring 26. Electric connections are made corresponding to the different positions of the lever 7 through the brushes or wipers 47 and segments or contact-rings 29, the latter suitably mounted upon the drum 85 28. The circuit is reversed through the reversing-switch contacts 32 by the switch 31, operated by cam 30, above referred to.

Upon the tube 9 is a cam 10, shown in 90 Figs. 1, 5 and 6; which controls the main switch mechanism contained in the case 13. A lever 16, pivoted at 17, carries the contact 14, which closes the circuit through clips 15. The movement of the lever 16 is controlled by the spring-pressed locking 95 pawl 12, operated by the pin 11, which in turn is operated by the cam 10. In the position shown in Figs. 1 and 5, the cam is engaging the pin, releasing the pawl, and permitting the closing of the switch contacts 15 100 by the movement of the lever 16; while in Fig. 6, the cam 10 is not in engagement

with the pin 11, the pawl 12 is pressed by spring 22 and engages the lever 16, preventing the closing of the circuit. The lower end of lever 16 is connected, through link 38, with the locking-pawl 39, which engages the ratchet 40. This ratchet is connected through the levers 43, 44 and 45, with the treadle 46, the levers 45 and 43 controlling the brake-strap 41 on the brake-drum 42.

10 The switch-case 13 also carries the lighting switch 23.

The operation of the controller is as follows:—The lever 7 rests on the lower ahead sector 6 and is moved forward on this sector for the different speeds ahead. The lever cannot be lifted as long as it is in the running ahead position, as the lower ahead sector guides the lever, in lever guide slot 50. When it is necessary to shut off the power 20 while going ahead, the lever is moved back until it strikes the upper reversing sector 5, which acts as a stop at the off point, while the lever is prevented from being moved off the lower ahead sector at its full 25 speed point by the stop 19.

In order to reverse the controller, the controller lever 7 can only be raised while it is in the off position in order to cause the upper reversing sector to engage the lever 30 guide slot 50, the open space 20 permitting the controlling lever to be raised and lowered from the upper sector to the lower sector in this off position only. When the lever is in full speed reversing position it is prevented from moving off the upper sector by 35 the stop 18.

The switching is accomplished as follows:—The running switch lever 16 is moved by the handle 21 ahead for closing the main 40 circuit by pushing the insulated contact 14 into the clips 15, which can only be accomplished when the cam projection 10 has moved the locking pin 11 in, moving the pawl 12 out of the path of the switch lever. 45 Should the controller be in any running position, either the ahead or reverse position, however, the cam projection leaves the pin 11, which causes the spring 22 to move the pawl 12 into the path of the switch lever, 50 preventing the switch from being closed until the controller is put into the off position, thereby safeguarding the automobile from being started unconsciously, preventing accidents, runaways and collisions.

55 The locking of brakes is accomplished as follows:—The switch lever 16 is connected to the pawl 39 by means of suitable links and cranks. To lock the brakes, the brake foot pedal 46 is pushed forward which 60 causes the brake strap 41 to contract around the brake drum 42, then the switch handle 21 is pushed in the backward direction, causing the pawl 39 to engage the teeth of ratchet 40, locking the brakes, which remain

locked until the pedal is moved forward 65 slightly to relieve the strain on the pawl before the switch lever can be moved forward; it is therefore impossible to throw in the running switch with brakes locked, as the switch lever must unlock the brakes before 70 it can be thrown ahead to close the main circuit. Braking while running is done by the foot treadle only and cannot be locked while running. The reversing switch 31 is actuated by the reversing-switch cam 30, which 75 throws the switch on reversing only, it being the object of this invention is to reduce the friction, which is common to controllers, to a minimum, and it will be seen that the cam 30 does not engage the reversing switch in 80 the ahead position, which does away with the friction entirely in one direction.

The insulated drum 28 carries the contact rings 29, which make necessary contacts at the various points with the wiper contacts 85 47, while quick making and breaking of contacts are accomplished by the controller action cam 25, and the snap effect is produced at each step by the action of lever 27 and the roller 52, which latter is carried by this lever 90 and is held in tension by the spring 26.

The steering is accomplished by moving the steering handle bar 2, which imparts rotary motion to the steering shaft 35, which moves the steering crank 36 to actuate the 95 steering rod 37, which causes the front wheels to change their angular position relative to its axis.

I claim:—

1. In an automobile controller, the combination of a lever, "ahead" and "reverse" sectors out of alignment, means on said lever preventing movement from one sector to the other without a change in direction of movement of said lever, and stops to limit the 105 movement of said lever.

2. In an automobile controller, the combination of a lever, spaced "ahead" and "reverse" sectors, said space constituting the "off" position, means on said lever coöperating with said sectors preventing the movement from one sector to the other without passing through the "off" position, a switch, and means controlled by said lever for unlocking said switch when the lever is in the 115 "off" position.

3. In an automobile controller, the combination of a lever, controller contacts operated by said lever, a locking device giving a step-by-step movement to said controller contacts, a current-reversing switch mechanically disconnected when said lever is in the "ahead" position thereby avoiding friction, and mechanically connected when the lever is in the "reverse" position.

4. In an automobile controller, the combination of a lever, a main switch, a locking means for said switch, means controlled by

said lever to operate said locking means and release said switch, a foot-brake mechanism, a ratchet connected to said foot-brake mechanism, a pawl operated by said main switch, 5 said pawl arranged to engage said ratchet by a movement of said switch and lock the brake in the "braked" position.

In testimony whereof I affix my signature in presence of two witnesses.

OLIVER P. FRITCHLE.
